CARBURETOR APPARATUS

Charles Vance Dame, Lanark, Ill.

Application December 18, 1933, Serial No. 702,889

10 Claims. (Cl. 261—18)

This invention relates to improvements in carburetor apparatus.

One object of the invention is to provide carburetor apparatus which is controllable for varying the quantity, mixture, and character of the fuel in accordance with the requirements of the engine under different loads and under various conditions.

Another object of the invention is to provide 10 a carburetor which may be adjusted by the driver of the vehicle to shut off the fuel intake, as when a vehicle is coasting down grade, for example, and admit air only to the cylinders whereby the engine acts as a brake to retard the movement of the vehicle without the consumption of fuel.

A further object of the invention is to provide 20 a carburetor which is adapted to supply fuels of different character to the engine as conditions may render desirable, for example, in starting the engine, highly volatile gasoline may be delivered to the cylinders and after the engine has become warm, a lower grade of fuel, as kerosene, may be supplied or when the engine, using a low 25 grade fuel, is laboring under a heavy load, the low grade fuel may be supplemented by fuel of higher grade. Other adjustments of the carburetor, operable from driving position, permit of the adding of water vapor to the fuel mixture, or admitting cool or hot air to the fuel mixture within a mixing chamber of the carburetor to make a leaner fuel when required.

Another object of the invention is to provide 30 a carburetor apparatus which by a vortex of air atomizes the fuel and by the centrifugal action of the air throws the larger particles of fuel upon an absorbent lining of a chamber where it is volatilized by heat from a surrounding heating chamber, thereby preventing the introduction 35 of insufficiently atomized fuel into the combustion chambers of the engine.

An additional object is to provide a carburetor 40 having a conical valve within a mixing chamber for controlling the admission of vaporized fuel to the engine and by constricting the fuel passage between the vaporizing chamber and mixing chamber to increase the velocity of the fuel and air to further mix the same and also 45 to effect the mixture within the mixing chamber of the vaporized fuel with supplemental fuel added thereto or with air or water vapor.

A further object of the invention is to provide 50 annular intakes for the various gases entering the mixing chamber whereby the gas streams are

given annular form which in commingling in the chamber form a fuel of uniform mixture.

Another object of the invention is to provide a carburetor having controllable fuel and air intakes whereby a relatively uniform compression within the combustion chambers of the engine can be maintained whether the engine is operating under low or heavy load and the proper ratio of air to fuel also maintained to insure of complete combustion of the fuel.

Other objects relate to various features of construction and arrangement of parts which will be apparent from a consideration of the following specification and accompanying drawings, wherein:

Figure 1 is a broken vertical sectional view taken along line 1—1 of Figure 3.

Figure 2 is a similar sectional view showing the valves and various ports in open position.

Figure 3 is a horizontal section taken on line 20 3—3 of Figure 1.

Figure 4 is a sectional view taken on line 4—4 of Figure 1.

Figure 5 is a horizontal section taken on line 25 5—5 of Figure 1.

Figure 6 is a broken vertical sectional view taken on line 6—6 of Figure 1.

Figure 7 is a section taken on line 7—7 of Figure 1.

Figure 8 is an enlarged view partly in section 30 showing the manual control means for various ports and valves.

Figure 9 is a horizontal section somewhat enlarged taken on line 9—9 of Figure 8.

Figure 10 is a broken section taken on line 35 10—10 of Figure 9.

Figure 11 is an enlarged vertical section taken on line 11—11 of Figure 8.

Figure 12 is a broken end elevation looking to the left of Figure 8, and illustrating various 40 positions of the shaft operating arms.

Figure 13 is a vertical transverse detail sectional view illustrating a modification of the improvements.

In the drawings 10 indicates a liquid fuel receptacle of annular form having a float 11 there- 45 in connected to a valve 12 for operating the same to regulate the level of the fuel in the receptacle 12 which flows thereto through a pipe 13 from a fuel tank, not shown. The receptacle 10 is at- 50 tached to the annular depending flange 14 of the horizontal partition 15 which extends throughout the width and length of the exterior casing 16. Positioned within the chamber 17 defined by the wall or flange 14 is a circular 55

plate 18 spaced slightly beneath the partition 15. The plate 18 is shown provided with a central pocket 19 through which the fuel conveying tubes 20 (two of which only are shown) extend.

5 The tubes at their lower ends project into the fuel receptacle 10 and terminate, as shown in Figure 1, adjacent the opening 21 of the vaporizing chamber 22.

10 A cone shaped valve 23 is arranged to seat in the upper end of the cylindrical wall 24 of the chamber for preventing the passage of vaporized fuel into the mixing chamber 25 as hereinafter described.

15 Located in the mixing chamber 25 is a guide member 26 along the vertical walls of which the throttle valve 23 is guided. The member 26 not only guides the throttle valve 23 vertically, but it serves as a filler within the mixing chamber and reduces its effective volume so as to avoid the 20 deceleration of the gases or fuel passing therethrough to the intake manifold shown fragmentarily at 21. The throttle valve 23 is provided with brackets or arms 28 which at their lower ends are connected to a cross head 29. The 25 cross head is secured to a rod 30 which is slidably journaled in the sleeve 31 carried by the stationary bracket 32. Attached to the upper end of the rod 30 is a hollow piston 33 having a sliding fit with the cylindrical wall 34 of the closure member 35 which is located centrally of the 30 annular fuel receptacle 10.

The lower end of the rod 30 is provided with a head 36 mounted on the cam 37 which is operable by the main shaft 38. The shaft is provided with an operating arm 39 adapted to be attached to the conventional accelerator pedal, not shown, of the vehicle by any suitable means, such as by link 40.

When the shaft 38 and the cam 37 are in the 40 position shown in Figure 1, the throttle valve 23 is held positively in closed position. When the shaft is operated to release the cam member 36 a spring 41, which is disposed between the sleeve 31 and the cross head 29, tends to move the rod 30, cross head 29, arms 28, and valve 30 upwardly slightly so that the latter clears its seat 42.

When suction prevails in the chamber 25 due to the starting or operation of the engine, the piston 33 will move upwardly against the action 50 of the spring 43 to the extent permitted by the cam 37, and the movement of the piston or rod 33 by the atmospheric pressure, or by the suction, in other words, causes the port closure members 44 to uncover the ports 45 wholly or partially and 55 admit external air to the chamber 17.

The air will be drawn into the space between the horizontal partition 15 and the annular plate 18 and will form a vortex within the vaporizing chamber 22. Fuel is siphoned from the receptacle 10 through the tubes 20 and is atomized within the chamber 22. Due to the swirling action set up by the movement of air between the plate 18 and partition 15, the coarser particles of the fuel will be thrown against the absorbent lining 46 and thus will not pass upwardly past the throttle valve 23 into the mixing chamber 25 until it has been vaporized by heat transmitted to the chamber 22 by hot gases within the surrounding passage 47. This passage is defined by the vertical wall of the chamber 22 and a surrounding jacket 48.

70 The combustible gas formed by the mixture of the atomized fuel and the air taken in through ports 44, is drawn by suction of the engine 75 through the manifold 27 for admission to the

engine, not shown. The conical shaped throttle valve 23 serves to further mix the atomized fuel and air as it passes along the sides of the valve.

By means hereinafter described, the main portion of the carburetor above described may be employed alone or may be used in conjunction with other fuel or air admitting structure operatively associated therewith. Thus, on the left hand side of the main or central portion of the carburetor, there is shown an additional fuel 10 receptacle 49 having a float 50 therein which controls the inlet valve 51 through which fuel is supplied by a pipe 52, which communicates with a suitable supply tank, not shown.

The fuel admitted to this auxiliary carburetor 15 may be gasoline, and if the fuel used in the main carburetor section is heavy fuel such as kerosene or the like, the lighter fuel may be employed for starting the engine, and after the same has started and become sufficiently warm, 20 the auxiliary carburetor may be rendered inoperative and the main carburetor employed exclusively.

The auxiliary carburetor shown in the left hand side of Figure 1, may also be employed for 25 admitting air only to the mixing chamber 23, to supplement the gaseous mixture supplied to the mixing chamber by the main carburetor. The auxiliary carburetor is shown provided with fuel tubes 53 extending from the fuel within the 30 receptacle 49 into Venturi tubes 54 which project downwardly from the wall 55, which is secured to the partition 15, centrally of the upstanding tubular projection 56.

A conical valve 57 is adapted to seat on the 35 upper end of the projection 56 and has a tubular stem 58 provided with air inlet ports 58a at its lower end which admit atmospheric air to the interior of the valve. The tubular stem 58 is guided in its vertical movements by a sleeve 59 which is 40 supported by the wall 55. The sleeve 59 is shown provided with an outwardly extending flange 60 at its lower end between which and a collar or flange 61 on the stem 58 is disposed a spring 62 which tends to move the stem downwardly and 45 hold the valve 57 on its seat at the upper end of the extension 56.

Located on the top of the partition 55 is a rotatable closure plate 63 provided with ports 64 which are adapted to register with the upper ends 50 of the Venturi tubes 54 in certain positions of adjustment to the plate 63 (see Figure 4). The plate 63 is provided with a rack 65 which meshes with a pinion 66 carried by the operating shaft 67 having a bevel pinion 68 at its lower end. The 55 pinion 68 meshes with a similar bevel pinion 69 carried by the main shaft 38.

By proper rotation of the shaft 67 the plate 63 can be moved to bring the ports 64 into partial or complete registration with the Venturi tubes 54. 60

When the plate 63 is in the last named position, the air ports 70 in the wall 55 will be out of registration with the ports 71 of the plate 63.

Slidably mounted on the sleeve 59 is a piston 72 65 connected with which are arms 73 which carry closure members 74 and 75 which cooperate respectively with air inlet ports 76 and 77 by means of which air can be admitted to the chamber 78 defined by the end wall 79, by the casing partition 70 75, and bottom wall 80.

The valve 57 may be moved upwardly by suction prevailing within the chamber 81 when the cam 62 has been moved to position to release the stem, as hereinafter explained. The suction from

the engine is transmitted to the chamber 81 through the mixing chamber 25 and passage 83, the upper end of which, however, is adapted to be closed by a valve 84. When the valve 84 has

- 5 been elevated by means of the arms 85 which are connected at their lower ends to a cross head 86 attached to a lift rod 87 which is operable by a cam 88 mounted on shaft 38, the suction of the engine will be transmitted through passage 83 to the chamber 81, whereupon the greater external air pressure acting on the interior of the valve through the ports 58a will raise the valve against the action of the spring 62. If the plate 63 has been rotated to the opposite position shown in 10 Figure 1, that is, to the position where the ports 70 and 71 are closed and ports 64 opened, fuel will be drawn through the tubes 53 by the passage of air through the Venturi tubes 54. The reduction of pressure within the chamber 18 tends to move the piston 72 upwardly to elevate the port closing members 14 and 15.

Thus in the position shown in Figure 1, air will be admitted through the tube 89 which may deliver warm or hot air. This air entering the chamber 18, passes through the Venturi tubes 54 and elevates the fuel through the tubes 53 and carries the same past the open valve 57 into the chamber 81. Due to the conical shape of the valve the heavy particles of fuel will be thrown against the absorbent lining 90 and there remain until vaporized by heat in the surrounding chamber 91. The source of heat for chamber 91 may be exhaust gases from the engine which enter at 92 and pass into chamber 93, and from thence through the passage 94 formed by the horizontal walls 15 and 95.

It will be noted that this passage 94 communicates with the previously described heating passage 47 which supplies heat to the vaporizing chamber 22. The hot gases continue through the passage 94 at the left side of the central portion of the device and enter the chamber 91 at the extreme left hand side of the apparatus. The gases pass outwardly through the exhaust tube 96.

The circulation of the exhaust gases for heating various parts of the apparatus is indicated by arrows having broken shafts. It will thus be seen that with the throttle valve 23 closed and the valve 84 open and the closure plate 63 rotated to open the Venturi tubes 54, as shown in Figure 2, fuel from the receptacle 49 can be drawn into the engine.

The fuel last mentioned may, of course, be gasoline as previously stated, for starting the engine, and when the engine is sufficiently warmed, the various closure members may be operated to admit heavier fuel from the main carburetor, as described.

60 The fuel from the auxiliary carburetor may be operated also to deliver fuel to the engine to supplement the fuel delivered by the main carburetor section of the apparatus.

Thus when the engine is under a heavy load, 65 the auxiliary carburetor may be actuated to deliver gasoline vapor fuel to the engine to increase its power.

Mechanism for independently actuating the closure plate 63 of the auxiliary carburetor is 70 shown in Figures 1, 2, 8, 9 and 10. Secured to the shaft 61 is a manually operable arm or lever 97 to which a link or wire may be attached whereby the shaft can be swung from driving position. As shown in Figure 10, a spring 98 has one end secured to the lever 97, while the other

end of the spring is attached to the hub 99 which is pinned at 100 to the short extension 101 of shaft 67, the extension carrying the bevel gear 68.

Thus, when it is desired to shift the plate 63 to open the Venturi tubes 54 and close the ports 70 and 71, the operator swings the lever 97 against the action of the spring 98 to rotate the shaft 67. The turning resistance of shaft 38 is sufficient to resist displacement of the shaft 10 under the tension of the spring 98.

When the Venturi tubes 54 are closed and the cam 82 is in position to permit the valve 57 to move upwardly under suction of the engine when the closure valve plate 84 is elevated, air only 15 will be drawn through the auxiliary carburetor and thence through passage 83 to the mixing chamber 25 where it will be mixed with fuel delivered to the mixing chamber by the main carburetor. This arrangement permits the control 20 of the quantity of air delivered to the mixing chamber 25, and thus the operator can vary the richness of the fuel taken into the engine. The proper proportions of air and fuel can thus be obtained for securing the maximum efficiency by 25 the individual regulation of the air provided for by the auxiliary carburetor section.

At the right hand side of the structure shown in Figures 1 and 2 is a third float chamber 102, having therein a float 103 which controls the 30 valve 104 in the pipe line 105 by means of which an additional fuel or preferably water is delivered to the chamber. The construction of this third auxiliary carburetor section is similar to the first auxiliary carburetor in that it is provided with tubes 106 which project from the chamber 102 into Venturi tubes 107 by means of which water vapor may be carried through the chamber 108 and tube 109 into the heated chamber 110 when the valve 111 is open. This water 40 vapor will be carried into the chamber 110, the walls of which are provided with an absorbent lining 112 which may be of asbestos to absorb any insufficiently atomized water particles which will be thrown against the absorbent material by 45 the conical walls of the valve 111.

The water vapor will pass from the chamber 110 into the horizontal passage 113 and into the mixing chamber 25 when the closure plate or valve 114 is elevated.

The valve 111 has a hollow stem 115 which is provided with ports 116 to admit atmospheric air to the interior of the valve whereby the latter will be lifted by air pressure when suction from the chamber 25 is transmitted by passage 113 to 50 the chamber 110.

Either hot or cold air will be admitted to the chamber 117 through ports 118 and 119 respectively depending on the position of the valve closure members 120, 121. These closure members 60 are carried by arms 122 attached to the piston 123 which is slid able under external air pressure along the guiding sleeve 124 through which the stem 115 of the valve passes.

The closing valve 114 for the passage 113 is 65 carried by arms or brackets 125 which are carried by cross head 126. The cross head is secured to a rod 127 having a cam engaging member 128 at its lower end. This member cooperates with a cam 129 mounted on the shaft 38 for positively lifting the valve closure 114.

A spring 130 disposed between the bearing sleeve 131 and the member 128 tends to return the cross head 126 and arms 125 and valve clo- 75

sure member 114 to the position shown in Figure 1.

The stem 115 is moved to closed position normally by the spring 132. A cam 133 located on the shaft 38 around which extends the follower 134 is adapted to hold the valve 111 closed when the shaft 38 is in the position shown in Figure 1. When the shaft is operated as hereinafter mentioned to release the valve stem, the suction from the engine will lift the valve 111 when the closure member 114 is open and draw water vapor into the mixing chamber 25 to be commingled with the explosive mixture delivered either by the main carburetor section or the auxiliary carburetor section above described.

The passage of the air into the water vaporizing section of the apparatus and the path of the water vapor is indicated by double headed arrows in Figure 2.

It will be noted in Figure 2 that valves 23, 57 and 111 as well as closure members 84 and 114 are shown in open position, but it will be understood that this is not the normal operating arrangement of the carburetor apparatus. The water vapor may be delivered to the mixing chamber when one or the other of the main or auxiliary carburetor sections is in use. However, since the auxiliary section may be thrown into operation to supplement the main section, the water vapor may, of course, be simultaneously delivered should conditions warrant the use of the water vapor.

Referring to Figure 8 of the drawings, it will be seen that cams 88 and 129 which respectively operate the rods 87 and 127, controlling the opening of the closure members 84 and 114, are mounted for rotation upon the shaft 38. Cam 88 is provided with a laterally extending sleeve 88a upon which is secured a gear 135 which meshes with the pinion 136 secured on a shaft 137. The cam 129 is provided with a laterally extending sleeve 129a upon which is mounted a gear 138 which meshes with a pinion 139, also secured to the shaft 137. A pinion 140 is shown mounted at the left hand end of shaft 137 in Figure 8, and meshes with the gear 141 which is secured to an extension 82a of cam 88.

When the arm 39 of the shaft 38 is in the position shown in Figures 1 and 8, the cams 87 is in locking position, that is, it holds the push rod 138 in lowermost position, and thus holds the throttle valve 23 in the closed position shown in Figure 1.

The cam 133 likewise holds valve 111 in closed position when the arm 38 is in the position shown in Figures 1 and 8.

The cam 82 similarly holds valve 57 in closed position.

Upon swinging the arm 39 to the dotted line position shown in Figure 12, the various valves 23, 58, and 111 are released so that when suction prevails in their respective enclosing chambers the valves will be lifted against the action of the springs 43, 62 and 132 respectively. It will be seen that, although cams 82 and 133 are in position to release the respective valve, the latter will not open unless the closure members 84 and 114 are open.

These closure members are held closed by the springs mounted on the respective push rods 87 and 127, and are opened positively by the cams 88 and 129 respectively. To operate the cams 88 and 127 to open the closure members 84 and 114, the shaft 137 must be rotated. This shaft is provided with an operating lever 142 connected on

a suitable operating member 143, which is located for operation from driving position.

When the arm 142 is in a position shown by full lines in Figure 12, both cams 88 and 129 will be in the position shown in Figure 8, that is, in the position whereby the respective springs of the push rods 87 and 127 will hold the members 84 and 114 respectively in closed position.

Upon swinging the arm 142 to the dotted line position A, the pinion 140 will have operated gear 141 sufficiently to move the cam 82 to valve releasing position. Likewise pinion 136 will have moved gear 135 and cam 88 to the position shown in Figure 2, wherein the push rod 87 has been elevated and closure member 84 raised to admit fuel or air from the auxiliary carburetor section.

Movement of the arm 142 to the dotted line position B of Figure 12 will retain the closure member 84 in open position and will open closure member 114. In this position fuel or air from the auxiliary carburetor may be admitted to the mixing chamber 25, as well as water vapor from the water vaporizing section of the apparatus.

Movement of the arm 142 to the position indicated at C in Figure 12 will result in the closing of the closure member 84 but will retain the closure member 114 in open position.

The cams 88 and 129 are shaped, and so geared to the shaft 137 that this movement will be effected.

As shown in Figure 7, the cam followers or shoes 128 and 128a extend laterally over the respective cams 129 and 88 since the push rods 89 and 127 are offset from the longitudinal axis of the bracket 32 to avoid interference between the operation of the cross heads 86 and 128.

If the three main valves of the carburetor apparatus are closed as shown in Figure 1, and it is desired to start the engine in conjunction with which the apparatus is employed, the arm 142 will be manually moved to position A, assuming it is desired to start the engine on the fuel of the auxiliary carburetor section. The result of this movement of the arm is to release the valve 57 and open the closure member 84. When the engine is cranked, the suction will be directed from the mixing chamber 25 through passage 83 into mixing chamber 81. The valve 57 will be lifted and air will be drawn through the Venturi tubes 54, the arm 97 having also been moved to close the air ports 70 and 71 and effect the registration of ports 64 with the Venturi tubes.

If the ports 70 and 71 are fully closed a rich starting mixture will be provided for starting purposes and thereafter by moving the arm 97 to 55 partially close the Venturi tubes 54, and opening the ports 70 and 71, a leaner mixture will be provided. When the engine has been sufficiently warmed, the arm 39 of the main shaft 38 may be moved to the dotted line position of Figure 12, 60 and arm 142 moved to the full line position of said figure. This will cut off the fuel from the auxiliary carburetor section and admit fuel from the main carburetor section, that is, the fuel from the receptacle 10.

If it is desired to render the fuel mixture delivered by the main carburetor section more lean, air can be admitted through the auxiliary carburetor section by suitably operating the lever 97 as above described.

If it be desired to admit water vapor to the mixing chamber 25, the arm 142 is moved to position C of Figure 12, which movement effects the rotation of the cam 128 to lift the rod 127 and open closure member 114. The valve 111 will

be lifted by suction when the closure member 114 is elevated since the operation of the lever 39 to throw the main carburetor section into operation also moves the cam 133 from locking position.

5 The cam 37 holds the valve 23 closed when the shaft 38 is in the position shown in Figure 1. When the shaft is rotated to release the follower 36, the valve will rise under the suction of the engine as far as the cam permits. Upon decrease of engine speed, the spring 43 will move the valve toward closed position with the result that the velocity of the fuel past the valve will be maintained due to the constriction of the valve opening notwithstanding the decrease in suction 10 and thus a substantially uniform fuel mixture will be provided.

10 The carburetor apparatus enables the operator to regulate the gas mixture or select his particular fuel or employ water vapor as the requirements of the engine under varying conditions 15 may dictate. It also enables him to cut off the admission of all fuel to the engine and to admit only air thereto in regulated quantities. Thus when coasting down hill, the fuel may be shut off and air admitted to the engine through the auxiliary carburetor, which on the compression stroke of the engine retards its operation and acts as a brake without the consumption of fuel. If desired the admission of air may be eliminated 20 also whereby the pistons on the suction stroke will act against vacuum and an effective braking or retarding action obtained.

25 Another important advantage of the present improvements which provides for the controlled admission of fuel, air or water vapor, is that a substantially uniform compression can be provided in the engine cylinders whether operating under low or heavy load and at the same time the proper ratio of air and fuel maintained to insure proper combustion of the fuel and thus economy of operation. By opening the valve 23 partially by the appropriate rotation of the main shaft 38 to admit a limited quantity of fuel from the main carburetor, as when the engine is running under low load, the air intake through the auxiliary carburetor can also be controlled proportionately. If the valve 57 is opened to admit only the proper quantity of air to provide the proper air and fuel mixture in the mixing chamber 25 when the valve 23 is only partially open, the suction obtaining in the chamber 18 will be such that the piston 72 will be raised but little from the position shown in Figure 1 and hence hot air ports 76 will be open.

30 The hot expanded air, supplied by the tube 89 from any heat source, as from a heating jacket at the exhaust manifold of the engine, will be drawn into the mixing chamber 25 and thence to the engine. This expanded air and fuel mixture, being proportioned for complete combustion of the fuel molecules, will insure a higher compression in the engine on the compression stroke. This will insure more efficient operation of the engine under low load. When the engine is operating under full load, the valve 23 will have been opened to a greater extent by the rotation of the shaft 38 to admit more fuel to the mixing chamber 25. Such rotation of the shaft 38 will permit the valve 57 to be opened a greater extent and the increased suction in the chamber 18 will cause the piston 72 to move upwardly to effect the closing of the warm air ports 76 and the opening of cold air ports 77. The colder air, being more dense than the hot air, will be drawn 35 into the mixing chamber 25 and thence to the en-

gine cylinders and while the increased quantity of air provides sufficient oxygen for complete combustion, its greater density tends to prevent excessive compression. In other words, by the introduction of warm or hot air under low load and cold air at full load, a proper combustion mixture is obtained and a more uniform compression insured.

5 The same principle is employed in admitting water vapor to the engine since under low load 10 hot air will be admitted through ports 118, which will be supplied by tube 89a, while under full load the ports 119 will be opened to admit cooler air.

10 Under intermediate loads the hot air ports 76 15 and 118 will be partially closed and cold air ports 77 and 119 partially opened to provide air of suitable temperature to insure substantially constant compression, as will be seen.

15 The pocket or bowl 19 of the plate 18 provides 20 an area for the base of the vortex, while the upper ends of the tubes 20 are disposed at points of high velocity of the swirling air to best effect vaporization of the fuel and mixing of the same with the air. The swirling motion generated 25 within the vaporizing chamber 12 is transmitted to the mixing chamber also when valve 23 is open whereby a more thorough mixing of the gas in the mixing chamber is effected.

20 It will be noted also that the valves 23, 57 and 30 111, are raised to open position by the pressure of atmospheric air, which external air, being undisturbed by the flow of air or gases past the respective valves, tends to hold the same against fluttering action.

25 In Figure 13 a modification of the main carburetor section is shown which is similarly operable but has an annular supplementary air chamber 145 located above the mixing chamber 146. Air is admitted to the chamber 145 through in- 35 40 take 147. When the piston 148 is raised, the rods 149 elevate the closures 150 to uncover the ports 151 to admit the supplementary air into the pipe 152 which conveys the fuel mixture to the member 153 which may be an intake manifold of an 45 internal combustion engine or a suitable burner.

30 A plate 154, spaced from the partition 155 and defining therewith a passage 156, directs the air through the intake 157. The plate 154 and partition 155 function to form an air vortex within 50 the pipe 152 to effect a thorough mixing of the supplementary air with the gas fuel passing through the pipe, which swirling action of the fuel within the burner or combustion chambers accelerates combustion.

35 While I have shown and described certain structures embodying my improvements, I do not wish to be restricted specifically thereto except as so limited by the appended claims.

40 1. A carburetor comprising:

45 1. A carburetor comprising a vaporizing chamber having an opening for the admission of fuel and air, a fuel conduit having an outlet end disposed adjacent the opening of said chamber, a pair of smooth parallel plates adjacent said opening forming an air intake for said chamber and so spaced as to create an air vortex at said outlet end of said conduit and within said chamber whereby the fuel delivered by said conduit is atomized and carried into the chamber with a 50 swirling motion.

55 2. A carburetor comprising a vaporizing chamber provided with a lower end wall having a fuel intake opening located centrally of said wall, a fuel delivery tube having its discharge end dis- 55 60 65 70 75

- posed adjacent said opening, and a plate so spaced from said wall in parallelism therewith as to define an annular air intake passage adapted to create a vortex within said chamber and atomize the fuel delivered by said tube.
3. A carburetor comprising a vaporizing chamber having a circular discharge opening, a mixing chamber communicating therewith, a conical closure member in said mixing chamber having its apex extending through said opening and arranged to seat in said opening for closing the same, means for raising and lowering said closure member for regulating the passage of vaporized fuel to said mixing chamber, and a stationary filler member in said mixing chamber telescopically engaged by said closure member and cooperating with said closure member to prevent excessive deceleration of gases passing through said mixing chamber as said closure member is moved toward closing position.
4. A carburetor comprising a mixing chamber, a main vaporizing chamber having an outlet communicating with said mixing chamber, a conical closure member in said mixing chamber for controlling the passage of gas from said vaporizing chamber to said mixing chamber, a pair of auxiliary vaporizing chambers, a vapor carrying duct for each of said auxiliary vaporizing chambers extending to said mixing chamber and terminating in an annular closure member for each of said annular outlets, lift rods for each of said closure members, and cam controlled means for controlling the actuation of each of said rods.
5. A carburetor comprising a vaporizing chamber, a mixing chamber communicating therewith, a valve for regulating the flow of gas from the former to the latter, an enclosure communicating with said vaporizing chamber having a liquid fuel reservoir therein, means for delivering atomized fuel from said reservoir to said vaporizing chamber, an air inlet port for said enclosure, an atmospheric pressure responsive piston positioned in a wall of said enclosure, valve actuating means operatively connecting said piston with said valve, a closure member for said air port carried by said last mentioned means and actuatable thereby for uncovering said port as said valve is moved to open position by said piston, and manually operable means for controlling the movements of said piston.
6. A carburetor comprising a vaporizing chamber having an outlet and a fuel intake, a valve for controlling the passage of gas through said outlet, an enclosure communicating with said chamber through said intake, a liquid fuel receptacle in said enclosure, a fuel nozzle for delivering fuel from said receptacle to said chamber, an atmospheric pressure responsive piston positioned in a wall of said enclosure, an air inlet port in a wall of said enclosure, means operatively connecting said piston to said valve, a closure member for said port actuatable by said means, a manually operable shaft, and means actuatable by said shaft when moved in one direction for moving said connecting means in a direction to retain said valve in closed position and release said valve

when said shaft is moved in the opposite direction for rendering said valve and port closure member operable by said piston.

7. A carburetor comprising a mixing chamber, a main vaporizing chamber, a valve for regulating the passage of gas from said vaporizing chamber to said mixing chamber, an auxiliary vaporizing chamber, a valve for said auxiliary chamber, a duct extending from said auxiliary vaporizing chamber to said mixing chamber, means for supplying fuel to each of said vaporizing chambers, a manually operable shaft provided with cams for controlling the operation of said valves, and manually operable means for interrupting the flow of fuel to said auxiliary chamber and admitting air thereto for conveyance by said duct to said mixing chamber for mixture with fuel delivered thereto by said main vaporizing chamber.

8. A carburetor comprising a mixing chamber, a main carburetor section for delivering vaporized fuel thereto, an auxiliary carburetor section having a duct communicating with said mixing chamber, said auxiliary section comprising an enclosure provided with a fuel receptacle therein, a partition in said enclosure having a port for atomized fuel, a nozzle for delivering atomized fuel from said receptacle through said port to said auxiliary vaporizing chamber, said partition having an air port therein, a rotatable disk on said partition having openings therein for selective registration with said fuel port or said air port, a valve for each of said carburetor sections for controlling the delivery of fuel to said mixing chamber, cam actuated mechanism for controlling said valves, and means for actuating said disk for effecting the registration of an opening therein with said air port or said fuel port for delivering either air or fuel to said mixing chamber.

9. A carburetor comprising a mixing chamber arranged for communication with an engine intake, fuel vaporizing means for delivering fuel to said chamber, an auxiliary chamber having an outlet, a duct providing communication between said outlet and said mixing chamber, hot and cold air intake ports for said auxiliary chamber, closure members for regulating the passage of hot or cold air through said hot and cold air ports respectively, and an atmospheric pressure responsive member operatively connected with said closure members for shifting the same from closed to open positions and vice versa whereby warm air will be admitted to said mixing chamber under low engine loads and cold air under high engine loads.

10. A carburetor comprising a vaporizing chamber having an intake at one end and an outlet at the opposite end, a fibrous lining on the interior wall of said chamber, means for heating said lining, and means adjacent said intake end of said chamber for delivering atomized fuel therethrough with a swirling motion whereby the heavy particles of the fuel will be thrown against said heated lining for rapid dispersal and evaporation before passing through said outlet.

CHARLES VANCE DAME.
